UNITED STATES PATENT OFFICE.

STEPHEN WOODS, OF UPPER MONTCLAIR, NEW JERSEY.

SHEET-METAL CONTAINER.

1,177,160.

Specification of Letters Patent. Patented Mar. 28, 1916.

Application filed May 14, 1915. Serial No. 28,075.

To all whom it may concern:

Be it known that I, STEPHEN Woods, a citizen of the United States of America, residing at Upper Montclair, in the county of 5 Essex, State of New Jersey, have invented certain new and useful Improvements in Sheet-Metal Containers, of which the following is a specification.

My invention relates to improvements in 10 sheet metal containers and has as its object the production of such device in such manner that it will be extremely strong while easy and cheap to manufacture. Furthermore by the practice of my invention the 15 container produced is of extremely attractive appearance.

Other objects will appear in the following specification.

I shall describe one form of container embodying the principles of my invention in 20 connection with the accompanying drawings in which—

Figure 1 is a plan view of a blank for the body of the container. Fig. 2 is a plan view 25 of a blank for forming one of the legs or corners for the container. Fig. 3 is an isometric perspective view of the container set up and assembled, parts being broken away and parts being shown in dotted lines 30 for clearness of illustration. Fig. 4 is a cross sectional view through the end of the container, one of the corner or end leg members being shown in full lines. Fig. 5 is an elevation of one of the corner or leg members 35 detached. Fig. 6 is a sectional view along the bottom of the box at the corner, partly broken away.

Similar letters of reference indicate similar parts throughout the several views.

40 The blank shown in Fig. 1 may be stamped out of any suitable metal, silver or gold, or plated metal, or otherwise, as may be desired. In the blank *a*, *a* indicate the sides of the box, *b* the bottom, *c*, *c* the ends and *d*, *d*, *d*, *d* end portions or flaps on the respective sides and ends which may be turned over to form a dependent rim giving a curved upper edge to the assembled container, as shown at *e* in Figs. 3 and 4. *f*, *f* indicate 45 lugs in such relationship to each other that when the sides *a*, *a*, and ends *c*, *c* are bent or turned up along the lines *g*, *g*, said lugs will interlock as shown in Fig. 3. The lugs are 50 shown as being graduated in distance of pro-

jection from the top to the bottom for the 55 purpose hereinafter specified. *h*, *h* indicate perforations in the bottom *b* of the box for the purpose hereinafter specified.

The blank for forming the corner or leg member of the container shown in Fig. 2 is 60 stamped to form seats *i*, *i* and pins *j*, *j*, so that when the blank is bent up along the lines *k*, *k* to form the completed corner or leg member shown in Fig. 5, the pins *j*, *j* will be in position to come together and enter 65 perforations *h* in the bottom *b* of the container, the seats *i*, *i* forming a support for the bottom of the box when the corner or leg member is in place.

As shown in Fig. 3, an ear *l* may be 70 formed on the rear side of the two back corner or leg members to receive pin *m*, passing through hinged member *n* on cover *o* to form a hinge for connecting the cover and the box together.

75

In assembling the box after the ends and sides have been bent up as described and the edges *d*, *d* turned down and the lugs *f*, *f* have interlocked, the corner or leg members are slipped over the interlocked lugs at the 80 corners so that the pins *j* enter perforation *h*. The container being then in an inverted position, molten metal such as lead, or any suitable cementitious substance is run into the hollow leg filling the same to any desirable extent and firmly uniting the lugs, the filling material and the leg member together so that upon the cooling or the setting of the filling material, the leg members are immovable upon the corners and 90 the corners are held firmly together in locked position. The leg member being smaller at the top than at the bottom cannot, of course, pull off over the filling material which is firmly united to the interlocking lugs as described. The corner or leg members, it will be seen, perform a triple function viz: that of a leg, that of a corner and that of a mold for the reinforcement and uniting of the 95 corners of the container together.

100

It will be clear from the foregoing specification that by the means disclosed a container may be cheaply, quickly and effectively made without soldering, producing a structure of great strength and stability. 105 I am aware that the forms of the various parts may be changed without departing from the spirit of my invention and I do not

restrict myself to any such forms or other details further than the scope of the appended claims demands.

What I claim and desire to secure by 5 Letters Patent is:—

1. A sheet-metal container having interlocking corners comprising outwardly extending lugs formed on the edges of the side and end walls of the container substantially in the plane of said walls respectively and crossing each other at an angle, a form mounted on each of said corners but appreciably distant therefrom and a filler between said form and said corners.
- 15 2. A sheet-metal container having interlocking corners comprising outwardly extending lugs formed on the edges of the side and end walls of the container substantially in the plane of said walls respectively and 20 crossing each other at an angle, a hollow form mounted on each of said corners but having a space between said corners and the walls of said form and a filler between said form and said corners uniting the same 25 together.
3. A sheet-metal container comprising a body blank and a corner blank, the body blank being stamped to form the bottom, sides and ends of the container, the sides 30 and ends being formed with outwardly projecting lugs in the plane of said sides and ends respectively and adapted to interlock

when the sides and ends are bent up at right angles to the bottom and the corner blank being stamped to form a hollow leg to fit 35 the corners of the container.

4. A sheet-metal container comprising a body blank and a corner blank, the body blank being stamped to form the bottom, sides and ends of the container, the sides 40 and ends being formed with a plurality of lugs at each of the side edges thereof, the lugs increasing in distance of projection from the side edges of the sides and ends respectively from without inward and said lugs being adapted to interlock when the sides and ends are bent up at right angles to the bottom, and the corner blank being stamped to form a hollow leg to fit the corners of the container. 45

5. A sheet-metal container having a series of interlocking lugs at each corner increasing in distance of projection from the top downward, a hollow leg fitting over said lugs and a filler uniting said leg and said 50 lugs.

In testimony whereof I have signed this specification in the presence of two subscribing witnesses.

STEPHEN WOODS.
